H. E. ANDERSON

HAND BRAKE

Filed Oct. 9, 1922

UNITED STATES PATENT OFFICE.

HARLEY E. ANDERSON, OF CHICAGO, ILLINOIS, ASSIGNOR, BY MESNE ASSIGNMENTS,
TO W. H. MINER, INC., A CORPORATION OF DELAWARE.

HAND BRAKE.

Application filed October 9, 1922. Serial No. 593,457.

This invention relates to improvements in hand brakes for cars.

In the present practice, a common form of hand brake employed on railway cars is that of the drop handle lever and ratchet type. In this type of brake, a vertical staff, journaled in suitable bearings, is employed. In this type of vertical staff brake, and in fact, other types of vertical staff brakes, it frequently happens that the staff gets out of alignment with the rotating means at the top thereof, due sometimes to excessive strain on the staff and at other times to loosening of the usual lower step bearing. When this action occurs, it is obvious that there will be undue binding of the parts requiring excessive exertion upon the part of the brakeman in setting the brakes.

The object of my invention is to provide an exceedingly simple arrangement in hand brakes for railway cars, wherein the brake staff is so mounted as to prevent all binding of the bearings due to bending of the staff in service.

Another and more specific object of the invention is to provide an arrangement in hand brakes for railway cars wherein the brake staff and the ratchet member are joined by a universal rocking connection, which permits lateral movement of the staff relatively to the ratchet member, to allow for the bending or flexing of the staff during the application of the brakes without binding in the bearings.

Other objects will more clearly appear from the description and claims hereinafter following.

In the drawings forming a part of this specification, Figure 1 shows a vertical sectional view of a hand brake embodying my improvements. And Fig. 2 shows a horizontal sectional view taken substantially on the line 2-2 of Fig. 1.

In said drawings, 10 denotes the end wall of a car to which is secured a housing or bracket designated generally by the reference character A. The latter is formed with a back wall 11 secured to the car wall 10, and with a horizontally extending web 12 having a bearing opening 13 therein. Said bracket is also provided with a vertically extending arcuate wall or web 14 and a horizontally extending web or wall 15 located above the wall 12, having a curved face 16.

The usual vertical brake staff is indicated at 17, it being understood that the same will have a chain-winding means at its lower end receiving a chain connecting with and leading to the brake rigging. At the upper end, staff 17 is formed with a square portion 18 to receive a ball joint staff casting indicated generally by reference character B. The latter is formed with upper and lower cylindrical portions 19 and 20 and intermediate radially projecting teeth 21. As clearly shown in Fig. 1, each of the teeth 21 is tapered in a vertical direction and has a lower curved bearing surface 22.

Surrounding the ball joint staff casting B is a hollow ratchet member indicated generally by the reference character C. The latter is formed with the usual upper and lower peripheral ratchet teeth 23 and 24, respectively, which are separated by an intermediate cylindrical bearing flange 25, adapted to co-act with the curved bearing face 16 on the plate 15. The ratchet member is also provided with a lower reduced cylindrical bearing surface 26 received in the bearing opening 13 of the web 12. The hollow ratchet element C is provided interiorly thereof with inwardly projecting teeth 27 co-acting with the corresponding teeth 21 on the casting B. The teeth 27 are tapered outwardly to properly co-act with the teeth 21. The inner end faces of the teeth 27 are slightly spaced with reference to the faces 28 between the teeth 21, and the teeth 21 have their outer end faces 29 correspondingly spaced with reference to the faces between the teeth 27 to allow for a slight relative movement of the same radially with reference to the brake staff 17. The hollow ratchet member C is also provided with an annular inwardly projecting rib 30, below the teeth 27, said rib having an upper curved bearing surface 31 corresponding in curvature with the lower curved faces 22 of the teeth 21.

In this connection, it is pointed out that the cylindrical lower portion 20 of the casting B is arranged in spaced relation with reference to the rib 30 to allow for a limited radial movement of the casting B within the ratchet member C, and that the slight vertical taper of the teeth 21 allows for clearance during the rocking movement of the staff.

A carrier member 32 of generally cylind-

drical form is provided having a curved vertical wall 33 partially surrounding the ratchet member C, a bearing opening 43 receiving the upper cylindrical bearing portion 44 of the ratchet member C, and parallel laterally extending vertical walls 34 receiving therebetween the operating lever or handle 35. The latter is pivoted on the pin 36 passing through the parallel walls 10 34 and is provided with the usual spring pressed pawl 37 adapted to engage with the ratchet teeth 23 when the handle is held in horizontal operative position.

A cover plate 38 is provided for retaining 15 the carrier in position and preventing upward movement of the casting B within the ratchet member C. The cover plate 38 is held in fixed position on the bracket 13 by means of the bolt 39, passing through perforations in the cover plate 38 and the walls 12 and 15 of the bracket 11. A locking dog 40 is pivoted on the bolt 39 between the walls 12 and 15 for engagement with the ratchet teeth 24. Said locking dog 40 is 20 provided with an operating handle 41 and is held in yielding engagement with the ratchet teeth 24 by a spring 42 interposed between the ratchet engaging end of the dog and the rear wall 11 of the housing.

30 In the operation of my improved hand brake, the handle 35 is properly engaged with the ratchet member C in the usual manner, by raising the end of the handle 35 and the ratchet C is then rotated thereby 35 to wind the brake chain upon the staff 17 to tighten or apply the brakes. As the ratchet member C is rotated, the teeth thereon will cause the casting B to rotate therewith by engagement with the teeth on the latter, and thus impart rotary movement of the brake staff 17. In the event the staff 40 is bent or flexed under excessive chain-pull, or by reason of the usual lower step bearing becoming loosened or distorted, the lack of alinement thus caused is automatically taken care of by the universal connection between 45

the casting B and ratchet C above described, thus minimizing tendency to bind.

I have herein shown and described what I now consider the preferred manner of carrying out the invention, but the same is merely illustrative and I contemplate all changes and modifications that come within the scope of the claims appended hereto.

I claim:

1. In a device of the class described; a bearing member; a hollow ratchet element journaled in said bearing member, said ratchet element being provided on the interior thereof with a curved bearing surface and driving teeth; means for rotating said ratchet member; a brake staff extending into said ratchet element; a sleeve rigidly secured to said staff and having limited lateral movement within said ratchet element, said sleeve being provided with a curved bearing surface co-acting with said first named bearing surface and teeth engaging said first named teeth, said teeth having limited play in a direction radially of said staff.

2. In a hand brake mechanism, the combination with a brake staff adapted to be rotatably confined adjacent one end and adapted to have a brake tightening element connected therewith; of a support secured to the car structure; driving means including a driving member rotatably journaled in said support, said driving member being provided with an opening for the loose reception of said staff, and with a curved seat on its interior; of a rocking member associated with said staff and having a sliding and rocking engagement with said seat; and driving elements associated with said driving member and rocking member and arranged to permit movements therebetween while maintaining driving connection.

In witness that I claim the foregoing I have hereunto subscribed my name this 20th day of Sept. 1922.

HARLEY E. ANDERSON.
